DESIGN FOR AN ELECTRIC FAN

Henry W. Mackey and Guy M. Lane,
Detroit, Mich.

Application May 26, 1941, Serial No. 101,158

Term of patent 7 years

To all whom it may concern:

Be it known that we, Henry W. Mackey and Guy M. Lane, citizens of the United States of America, residing at Detroit, in the county of Wayne and State of Michigan, have invented a new, original, and ornamental Design for an Electric Fan, of which the following is a specification, reference being had therein to the accompanying drawing, forming a part thereof, wherein

The side opposite to that shown in Figure 2 is the same as that shown in Figure 2.

We claim:

The ornamental design for an electric fan, substantially as shown and described.

HENRY W. MACKEY.
GUY M. LANE.
